DRIVE OF WEFT INSERTERS IN
SHUTTLELESS LOOMS

Raymond Dewas, Amiens, France

Application July 3, 1951, Serial No. 235,007

Claims priority, application France July 13, 1950

6 Claims. (Cl. 139—123)

1

This invention relates to needle weaving looms, in which the weft is inserted either by a single weft inserter or needle traversing the shed, or by two oppositely arranged weft inserters or needles, one of which conducts the weft to the middle of the shed where it is taken up and drawn to the selvedge by the other weft inserter or needle.

The invention has reference to the movement of the picking arm operating the single weft inserter or needle for the insertion of the shoot, or of the two picking arms operating the oppositely arranged weft inserters or needles mentioned above, the picking arm, or each of the picking arms as the case may be, having to perform a double movement, i.e. a longitudinal oscillating movement alternately towards the interior and the exterior of the loom in a plane parallel to the batten, to cause the needle to enter and leave the shed, and the other, an oscillating movement with the batten alternately towards the front and the rear of the loom.

An important aim of the invention is to effect this double movement of the picking arms by means which provide permanently for perfect lubrication of the driving members causing the longitudinal oscillating movement, without risk of the lubricant escaping or being ejected outside the casing containing it, and also without risk of pieces of fluff, dust, or of foreign bodies entering the casing, so as to obtain the utmost cleanliness and safety of operation and, also, to effect numerous economies.

These results, as well as other results and features to be referred to hereinafter are obtained by the present invention in which the picking arm is pivotally mounted on the upper part of a casing having an oil bath in which the driving members for the said movement are enclosed, thus providing for the alternating longitudinal movement of the picking arm in a plane parallel to the batten, the casing itself being pivoted to allow of an alternating or rocking movement respectively towards the front and rear of the loom, in synchronism with the movement of the batten, the picking arm and the casing being located, at the place where normally the picking arm is pivotally mounted for oscillation in two planes, and so arranged that the opening made in the upper part of the casing for the passage of the picking arm is blocked as completely as possible by the parts used for the fitting.

It is another feature of the invention that, the ends of the casing are rotatably mounted on the lower rotating shaft, so that the casing can rock.

2

on the shaft, the shaft itself having keyed thereon an endlessly grooved cam, that is located inside the casing, and which acts to impart the oscillating movement to the picking arm that is pivoted on a spindle arranged in the upper part of the casing.

It is another feature of the invention that, the oscillating or rocking casing, when arranged near to the floor, is provided with extensions, arranged and co-operating with shields fixed to the floor, in such a way that no foreign object can be introduced between the floor and the oscillating casing.

It is another feature of the invention that, in looms with a single picking arm, the casing is made integral with the two swords of the batten by a crosspiece, thus constituting a rigid frame including the batten.

It is another feature of the invention that, in looms with oppositely arranged needles, the integral crosspiece of the swords of the batten connects the two casings of the two picking arms. Other characteristics and advantages of the invention will also be found in the following description of one form of construction which is given, simply by way of a non-limitative example and is diagrammatically shown in the attached drawings, in which:

Fig. 1 is a part sectional front elevation of the end of a batten of a loom with oppositely arranged needles showing a picking arm, the driving members therefore and the oscillating casing with its cover removed.

Fig. 2 is an end elevation of Fig. 1, the casing being sectioned on the line II—II of that figure and shown as occupying the forward position in its oscillating movement; and

Fig. 3 is a front view of the cover of the casing. Figure 4 shows in front elevation the two lay swords of the loom.

In the drawings, 1 is the batten having the channel 2 in which slides the weft inserter or needle, not shown, operated by the picking arm 3 by means of the connecting rod 4.

The batten 1 is attached to the swords 5 so that it can pivot about the axis of the lower shaft 6 supported by bearings 7 carried on the frame 8.

The casing 9 is rotatably mounted on the lower shaft 6 so that it can pivot freely thereon, the end plates 9a of the casing 9 forming bearings, therefore. The casing 9 is arranged to partake of the oscillating movement of the batten 1 by a connection consisting, in the example shown, of a crosspiece 10 fixed at 11 to the sword 5 and at

12 to the flange 9b that projects upwardly from the casing 9.

Within the casing 9 is arranged the cam 13 that is keyed on the lower rotating shaft 6 and is provided with an endless helicoidal groove 14 that engages with a roller 15, the spindle 16 of which is mounted in the lower end of the picking arm 3. The extreme positions taken by this roller, in the movement imparted to it by the groove 14, are indicated in Fig. 1 at 15' and 15'', whilst the corresponding positions of the picking arm 3 are indicated by the chain lines 3' and 3'' in that figure.

The casing 9 consists of a body, the profile of which is clearly shown in Fig. 2 having a front opening which is closed by a cover 17 tightly pressed against the front face of the casing 9 to which it is attached by nuts 18 screwed on to studs 19 mounted in or forming part of the casing 9, the cover 17 being provided with corresponding holes 33 as shown in Fig. 3.

The picking arm 3 is mounted on the upper part of the casing 9 from which it emerges so that it can oscillate freely to the extent required, the casing and the boss of the picking arm being arranged in such manner that the opening in the casing 9 through which the picking arm projects is completely closed, as far as possible as later shown.

To provide for the oscillation of the picking arm 3 it has a hub 3a traversed by a spindle 20 forming a journal for the arm, the spindle 20 being rigidly mounted on the upper thickened part 9c of the casing 9. The part 9c has a front face 9d of circular shape that serves as a face bearing, with the interposition of a washer 21, for the front face 22a of a bushing 22 fitted in one end of the cylindrical boss 3b that extends from the hub 3a of the picking arm 3. On the other side of the picking arm 3, the hub 3a also has a boss 3c that supports another bushing 22 having the face 22b that serves as a bearing for the inner face of the head 20a of the spindle 20. The hub 3a of the picking arm 3, the bosses 3b and 3c on opposite sides of the hub 3a, a bushing 22 fitted into the outer end of each boss, the head 20a of the spindle 20, the washer 21, and the cover 17 fitting tightly against the head substantially close the opening in the casing while permitting the picking arm 3 to oscillate.

When the picking arm 3 has been fitted and the shaft 20 tightened by means of the locknuts 23, the cover 17, having the upper central part 17a that is a close fit against the head 20a of the spindle 20, is secured in place by the nuts 18.

As the picking arm 3 is supported, at its pivotal point, by the spindle 20 mounted in the casing 9, which itself is pivotally mounted on the shaft 6 by the bearings in the end plates 9a, the picking arm and the needle are operated in a very precise manner, the benefit of which is shown, among other results, by the greater accuracy and regularity in the operation of the insertion of the weft.

In the case of looms with two opposite picking arms 3, shown in Fig. 4, the crosspiece 10, supported by the two swords 5 of the batten, connects the two corresponding casings 9, forming thus, with the batten, a rigid assembly.

In the case of looms with a single picking arm, a rigid assembly, in the same way, can be secured by connecting the casing by a crosspiece to the two swords of the batten.

The cover 17 of the casing 9 has a tapped hole 24 fitted with a threaded plug 25; the geometri-

cal axis of this hole coincides with that of the roller 15 when the picking arm 3 occupies the vertical position shown in Fig. 1, so that it is possible, by unscrewing the single plug 25, to verify the perfect tightening of the spindle 16 of the roller 15.

The casing 9 is provided, at its lower part, on the side opposite to the frame 8 of the loom, with two threaded holes 26 and 27 each closed by threaded plugs, the upper of which plugs enables the level 28 of the oil bath, in which the cam 13 splashes about, to be verified, whilst the lower plug enables the oil bath to be emptied.

To prevent any foreign object from getting accidentally under the oscillating casing 9, which might entail, when the next oscillation occurred, the jamming or fracture of the casing, the right and left hand sides of the casing have depending prolongations or flanges, 9e and 9f respectively, which prolongations or flanges, in combination with the raised sides, 29 and 30 respectively, of the shield of sheet material fixed to the floor, eliminate this risk.

To the same end the front part is protected by providing the cover 17 with the prolongation 17b in the form of a flap, the cross section of which as shown in Fig. 2 is in the form of an arc of a circle having its center on the axis of the shaft 6 around which the casing 9 pivots, in such a way that the prolongation 17b passes always at the same distance from the raised side 31 that may be integral with the raised sides 29 and 30, of the shield of sheet material fixed to the floor.

The rear part of the casing 9, behind the perpendicular plane through the axis of the shaft 6, is cylindrical and, in consequence, passes always at the same distance from the floor. However, to realise a complete framing on the four sides, there is provided a posterior raised side 32 of the shield of sheet material fixed to the floor.

It is to be understood that the invention is in no way limited to any particular form of construction but includes all variants, improvements of details and uses of equivalent means without, for this reason, exceeding its scope. Thus the oscillating movement of the case might be obtained, for instance, by connecting it to the batten 1 by a strut, in combination, or not, with the crosspiece 10.

The picking arm can of course control the needle by different arrangements, just as it can control two opposite needles by a known system of articulations. The picking arm can also put in action other members.

I claim:

1. Shuttleless looms having weft inserters, comprising a casing, driving members and a picking arm, said picking arm operating the weft inserter longitudinally to and fro for the insertion of the weft being pivotally mounted on the upper part of the casing having an oil bath containing the driving members for the said movement, the casing itself being pivoted to allow of an oscillating or rocking movement respectively towards the front and rear of the loom, in synchronism with the movement of the batten; the picking arm and the casing being located at the place where normally the picking arm is pivotally mounted for oscillation in two planes, said casing having an opening made in the upper part thereof for the passage of the picking arm, said picking arm having a hub at the pivotal mounting means thereof, a boss on each side of the hub, a bushing disposed in each boss, a head for

one side of the hub in juxtaposition with the outer surface of one bushing, and a washer for the other side of the hub in juxtaposition with the outer surface of the other bushing for substantially blocking the opening.

2. Shuttleless looms having weft inserters, as in claim 1, comprising a lower rotating shaft the ends of the casing being rotatably mounted on said lower rotating shaft, so that the casing can rock on the shaft, the shaft itself carrying an endlessly grooved cam, that is located inside the casing and which acts to impart the oscillating movement to the picking arm that is pivoted on a spindle arranged in the upper part of the casing.

3. Shuttleless looms having weft inserters as in claim 2, characterized in that the oscillating or rocking casing when arranged near to the floor, is provided with extensions, arranged and co-operating with shields fixed to the floor, in 20 such a way that no foreign object can be introduced between the floor and the oscillating casing.

4. Shuttleless looms having weft inserters, as in claim 2, comprising a cover for the casing, said 25

cover having an opening to enable the engagement of the roller with the cam to be inspected.

5. Shuttleless looms having weft inserters, as in claim 2, characterized in that, when having a single picking arm, the casing is connected with the swords of the batten by a crosspiece, thus constituting a rigid frame including the batten.

10 6. In shuttleless looms having weft inserters, as in claim 2, said looms having oppositely arranged weft inserters, a crosspiece connected with the swords of the batten and connecting the two casings, whereby the rigidity of the assembly is further increased.
